PORTABLE NURSERY SHELF

Michael Graboi, New York, N. Y., assignor to The Bonnytex Company, New York, N. Y., a copartnership

Application February 3, 1950, Serial No. 7,689

Term of patent 14 years

(Cl. D58—2)

To all whom it may concern:

Be it known that I, Michael Graboi, a citizen of the United States of America, residing in the city of New York, county of New York, State of New York, have invented a new, original, and ornamental Design for a Portable Nursery Shelf, of which the following is a specification, reference being had to the accompanying drawings, forming a part thereof, wherein:

Fig. 1 is a front perspective view of a portable nursery shelf showing my new design, the back thereof being plain; and

Fig. 2 is a perspective view thereof showing the portable nursery shelf in folded position.

The dominant features of my design are shown in full lines.

I claim:

The ornamental design for a portable nursery shelf, substantially as shown and described.

MICHAEL GRABOI.
